UNITED STATES PATENT OFFICE

2,515,362

CAN OPENER

Harry Von der Lieth, Ridgefield, N. J.

Application February 3, 1947, Serial No. 726,184

1 Claim. (CL 30—17)

1

This invention relates to a can opener, and more particularly to a device of this character that will clip onto the top of a can for the cutting off of the top thereof.

An object of the invention is to provide a can opener that is simple in construction and operation, adjustable in size for cans of various diameters, durable in use, and can be inexpensively manufactured.

With the above and other objects and advantages in view, the invention consists of the novel details of construction, arrangement and combination of parts more fully hereinafter described, claimed and illustrated in the accompanying drawings in which:

Figure 1 is a top plan view, partly in section, of an embodiment of the invention, in position on the top of a can;

Figure 2 is a side elevation of the can opener, partly in section, as applied to a can;

Figure 3 is a sectional view on the line 3—3 of Figure 2 looking in the direction of the arrows;

Figure 4 is a sectional view on the line 4—4 of Figure 2 looking in the direction of the arrows;

Figure 5 is a sectional view on the line 5—5 of Figure 1 looking in the direction of the arrows;

Figure 6 is a sectional view on the line 6—6 of Figure 1 looking in the direction of the arrows and

Figure 7 is a sectional view on the line 7—7 of Figure 1 looking in the direction of the arrows.

Referring more in detail to the drawings, the numeral 10 generally designates the can opener which comprises the substantially triangular shaped plate or body 11 which is provided with the depending peripheral flange 12. At the opposite corners of the base 13, cutting wheels 14, having annular cutting edges 15, are rotatably mounted on the depending pins 16 fixed in the plate 11.

At the center of the plate 11, a T-shaped handle 17 is rotatably mounted, and fixed to the end of the handle, under the plate 11, is a gear 18, which is in engagement with the rack teeth 19 formed on the inner side of the U-shaped thrust arm 20. Depending L-shaped guides 21 stamped from the plate 11 engage the arm 20 on the opposite side to the teeth 19 to slidably mount the arm on the plate 11, on the under surface thereof.

Rotatably mounted on the forward end of the arm 20 by a pin 22 fixed therein is a third cutting wheel 23 which is similar to cutting wheels 14 having the annular cutting edge 24.

In use, the handle 17 is turned to rotate the gear 18 which, engaging the teeth 19 on the arm 20, will move the cutting wheel 23 outwardly far enough to permit the cutting wheels to span the outer periphery of the can 25. Then by grasping

2

the can in one hand and turning the handle 17 in a clockwise manner, the cutting wheels will be drawn into engagement with the can, and puncture the can until the outer wheels engage the lid of the can and then upon further turning of the handle the plate will move about the axis of the can to cut the top therefrom.

There has been provided, a can opener which will accomplish the objects of the invention and from the foregoing description, it is believed the operation and construction of the device will be apparent to those skilled in the art.

It is also to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

A device of the character described, comprising a substantially triangular shaped plate-like body, a depending peripheral flange on said body adapted to engage a can top and support said body in spaced relation thereto, cutting wheels rotatably mounted on said body at opposite ends of the base of said body, said wheels mounted on said body and extending below said flange are adapted to cut the can below the top thereof, a handle mounted on said plate at the center thereof, a gear on the end of said handle below said body, a rack arm slidably mounted on said body in engagement with said gear, said gear and said rack arm lying within the flange of said body in a plane above the lower edge of said body so that said gear and said rack arm will not engage the can top during movement thereof and a cutting wheel rotatably mounted on the forward end of said arm which is moved inwardly and outwardly by said handle to vary the distance between said first cutting wheels and said last mentioned cutting wheels.
